UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

FURNACE AND PORT CONSTRUCTION

Application filed March 15, 1922. Serial No. 544,047.

This invention relates to a new and improved furnace and port construction and more particularly to such a construction applied to metallurgical furnaces of the open 5 hearth type.

As is well known in the art, furnaces of this type are double-ended and are periodically reversed in operation. The fuel and air necessary for combustion are introduced 10 through ports at one end of the furnace and the products of combustion are carried off through similar ports upon the opposite end of the furnace. The products of combustion serve to heat regenerative chambers which 15 upon reversal serve to preheat the incoming air or both the incoming air and the incoming fuel. Upon reversal of the furnace, the ports, which previously served to carry off the products of combustion, now serve to introduce the fuel and air, and the products of 20 combustion pass out through the ports which previously served as the incoming ports.

The volume of the products of combustion 25 considerably exceeds the volume of the incoming air and fuel. The size and design of the ports is, therefore, largely determined by the necessity for carrying off the products of combustion. It is, however, essential that the incoming air and fuel be properly directed and intermixed so as to produce a relatively short flame and that the flame be properly controlled. Where the ports serve both 30 as incoming and outgoing ports, it has been impossible to entirely reconcile the differing requirements of the incoming and outgoing 35 ports.

Certain previous inventions as, for example, the patent to McKune, No. 1,339,855, issued 40 May 11, 1920, have been directed toward remedying these defects by the provision of additional channels which serve upon the outgoing end to aid in carrying off the products of combustion.

It is an object of the present invention to 45 provide in furnaces of this type, having a combined port for the introduction of air and fuel, passages which communicate both with the port and the furnace chamber and means 50 adapted to selectively interrupt communi-

cation between the passages and the furnace chamber.

It is an additional object to provide in a construction of this character, passages 55 which have openings directly associated with the furnace chamber, the openings being of a size adequate for carrying off the products of combustion.

It is a further object to provide these passages with means adapted to interrupt their 60 communication with the furnace chamber so that they may serve upon the incoming end to introduce the air and to properly direct it into the combined air and fuel port.

It is also an object to provide a construction 65 which is simple in design and which may be readily applied to existing installations.

Other and further objects will appear as the description proceeds.

Broadly, my invention comprises the provision 70 in an open hearth furnace, having the combined air and fuel port, of air passages communicating with the combined air port and also with the furnace chamber, and means adapted to selectively interrupt communication 75 between the passages and the furnace chamber. In the particular embodiments of which I have shown herein, the interrupting means consists of water-cooled dampers.

I have illustrated a preferred embodiment 80 of my invention in the accompanying drawings, in which—

Figure 1 is a vertical section showing one 85 end of a furnace constructed according to the present invention;

Figure 2 is a horizontal section taken on line 2—2 of Figure 1; and

Figure 3 is a transverse vertical section taken on line 3—3 of Figure 2.

As shown in the drawings, the fuel uptake 90 6 is directed at 7 to the rear of the combined air and fuel port 8. This port 8 is directed into the end of the furnace chamber 9. It will be observed that the upper end of the gas port is covered at 10 and that the combined port is covered at 11. The space 12 exists between these covering portions and the roof 13 of the end of the furnace.

As shown in Figures 2 and 3, the air uptake 14 and 15 communicate with the com- 100

bined fuel and air port through transverse passages 16 and 17. The two air uptakes are provided with the dampers 18 and 19 respectively, which dampers operate on water-cooled guide-ways 20. It is to be understood that the gas and air uptakes lead to suitable regenerative chambers which may be of any usual construction and which are, therefore, not shown. The opposite end of the furnace is identical with that which has been shown.

In the operation of the furnace, upon the incoming end, the dampers 18 and 19 are in the inward position and serve to block off the upper end of the air uptakes. The air coming up through the uptakes is directed by the dampers through the lateral passages 16 and 17, and the air streams there meet the gas stream which comes up the uptake 6 and is directed through the opening 7 into the rear of the combined port. The lateral air passages, as shown, are of greater height where they enter the combined port than is the entrance 7 through which the gas enters the port.

The walls of the combined port converge toward each other so as to narrow the port toward the furnace proper. Air and gas are properly intermingled in this port and a relatively short, hot, effective flame is produced.

Upon the outgoing end, the dampers are drawn out and the products of combustion may directly enter the tops of the air uptakes. A portion of the products of combustion will enter the combined air and fuel port and thus go down the gas uptake and also pass through the lateral passages 16 and 17. However, the greater portion of these gases will pass over the top of the port and over the lateral continuations of this top and will pass directly down the air uptakes. This provision of greater area directly in communication with the furnace chamber upon the outgoing end serves to easily carry off the products of combustion without the necessity for forced draft means. It further permits the use of a relatively small incoming port properly designed to adequately mix the air and fuel and to efficiently direct and control the flame.

It is to be understood that the particular design of furnace shown is illustrative only and I reserve the right to make such changes and modifications as come within the spirit and scope of the appended claims.

I claim:

1. In an open hearth furnace, a combined air and fuel port, an air passage communicating with a side of the combined port and with the furnace chamber, and means adapted to selectively interrupt communication between the air passage and furnace chamber.

2. In an open hearth furnace, a combined air and fuel port, an air passage communi-

cating with the furnace chamber, a supplemental passage connecting the air passage and a side of the port, and means adapted to selectively direct air coming through said air passage into said supplemental passage and into the side of the combined port. 70

3. In an open hearth furnace, a combined air and fuel port, an air passage communicating with the furnace chamber, a supplemental passage connecting the air passage and a lateral portion of the port, and a damper adapted to selectively close off communication between the air passage and furnace chamber. 75

4. In an open hearth furnace, a combined air and fuel port, an air passage communicating with the furnace chamber, a diagonally extending supplemental passage connecting the air passage and a side of the port, and a damper located between the entrance of said supplemental diagonally extending passage 80 into the air passage and the entrance of the air passage into the furnace chamber adapted to selectively close off communication between the air passage and furnace chamber. 85

5. In an open hearth furnace, a combined air and fuel port, an air uptake communicating directly with the furnace chamber, a diagonally extending passage connecting the air uptake with an intermediate portion of the port, and means in the air uptake above 90 said diagonal passage adapted to selectively interrupt communication between the uptake and the furnace chamber. 95

6. In an open hearth furnace, a combined air and fuel port, an air uptake communicating directly with the furnace chamber, a transverse passage connecting the air uptake with the port, and a horizontally operating damper in the air uptake above said transverse passage adapted to selectively interrupt communication between the uptake and the furnace chamber. 100 105

7. In an open hearth furnace, a fuel uptake, an air uptake upon each side of the fuel uptake, a combined fuel and air port extending from the fuel uptake, and a diagonal passage connecting each air uptake to an intermediate portion of the port, the upper ends of the air uptakes being in direct communication with the furnace chamber. 110 115

8. In an open hearth furnace, a fuel uptake, an air uptake upon each side of the fuel uptake, a combined fuel and air port extending from the fuel uptake, a diagonal passage connecting each air uptake to an intermediate portion of the port, the upper ends of the air uptakes being in direct communication with the furnace chamber, and means in each air uptake adapted to selectively direct air into said diagonal passages. 120 125

9. In an open hearth furnace, a fuel uptake, an air uptake upon each side of the fuel uptake, a combined fuel and air port extending from the fuel uptake, a diagonal passage connecting each air uptake to an intermediate 130

portion of the port, the upper ends of the air uptakes being in direct communication with the furnace chamber, and a damper in each uptake adapted to selectively close the upper ends of said uptakes.

5 10. In an open hearth furnace, a fuel uptake, an air uptake upon each side of the fuel uptake, a combined fuel and air port extending from the fuel uptake, and a diagonal passage connecting each air uptake to an intermediate portion of the port, the entrance of the passages into the port extending the full depth of the port, the air uptakes being in communication with the furnace chamber.

10 15. In an open hearth furnace, a fuel uptake, an air uptake upon each side of the fuel uptake, a combined fuel and air port extending from the fuel uptake, and a diagonal passage connecting each air uptake to an intermediate portion of the port, the entrance of the passages into the port being of greater depth than the entrance of the fuel uptake into the port and extending higher than said latter entrance.

20 25. Signed at Chicago, Illinois, this 11th day of March, 1922.
